Patented Jan. 7, 1919.

UNITED STATES PATENT OFFICE.

JOHN H. DOWNS, OF JERSEY CITY, NEW JERSEY.

SUBMARINE BOMB.

1,290,125.

Specification of Letters Patent.

Patented Jan. 7, 1919.

Application filed January 12, 1918. Serial No. 211,583.

To all whom it may concern:

Be it known that I, JOHN H. DOWNS, a citizen of the United States, residing at Jersey City, in the county of Hudson and State 5 of New Jersey, have invented certain new and useful Improvements in Submarine Bombs, of which the following is a specification.

This invention relates to bombs adapted 10 to be fired from naval guns, or dropped by an aviator into the water in the neighborhood of an object of attack, and to be exploded by the action of the water.

The main object of the invention is to provide 15 a device of this character which can be set to explode a predetermined time after the bomb strikes the water, and which will also be exploded by contact with the target. To this end, the device comprises two separable 20 parts and trigger mechanism for firing the charge upon the separation of such parts. The parts are normally locked together and are separated as a result of pressure due to the passage of the bomb through the water.

25 In order that the invention may be clearly understood, reference is had to the accompanying drawings, forming part of this specification, in which one embodiment of the device is more or less conventionally illustrated, and in which,

Figure 1 is a longitudinal section through my improved bomb, parts being shown in elevation;

Fig. 2 is a front elevation thereof;

35 Fig. 3 is a transverse section on the line 3—3 of Fig. 1; and

Fig. 4 is a fragmentary section on an enlarged scale on the line 4—4 of Fig. 1, looking in the direction of the arrow.

40 Referring to the drawings in detail, my improved bomb comprises outer and inner cylindrical shells 1 and 3, the shell 1 being closed at the rear by a cap 2 and terminating in front in a pointed head 4. The shells 45 are formed of comparatively thin material, such as sheet material, while the head is preferably of thick cast metal so as to have sufficient weight to hold the bomb to a true course. The head 4 is preferably provided 50 with a transverse partition wall 5, and with a shouldered portion 6 which fits and is frictionally held within the end of the shell 1.

The inner shell 3 is rigidly secured at its front end to the head 4 and at its rear end is 55 closed by a plate 7, having a flange 8 which

snugly fits the outer shell and serves to maintain the inner shell properly centered.

Within the inner shell is a trigger mechanism designated in its entirety by the reference numeral 9, and comprising a plunger 10 actuated by a spring 11 and a trigger or detent 12. This trigger 12 is connected by means of a lanyard 13 with the plate 7. The plunger casing 9 is provided with a bail 14, which is also connected with the plate 7, a spring 15 being interposed in such connection.

The exploding charge is located at the front end of the inner shell and is designated by the numeral 17. Associated with 70 the charge is a suitable detonating cap 16, or the like, adapted to be fired by the plunger 10. At the opposite end of the charge is a second detonating cap 18, arranged to be engaged by the inner end of a firing pin 19, 75 extending through the partition wall 5 and having its outer end projecting slightly from the point of the head 4. This firing pin, of course, serves to explode the charge in case the end of the pin strikes the target or other 80 solid object.

The inner and outer shells 1 and 3 are normally locked together by suitable interlocking parts, such, for example, as the lugs 20 and 21. In order to explode the charge 85 a predetermined time after the bomb enters the water, means are provided for releasing or disengaging the lugs 20 and 21 from each other, such means being operated by the water. The means here shown comprises a piston 25, carrying a plunger 24, having a pointed end adapted to engage between the beveled face 22 of the lug 20 and the lug 21, a suitable notch or opening 23 being formed in the lugs to permit the point 90 of the plunger to enter. The piston 25 works in a cylinder 26, secured to the head 4, and communicating at its forward end with a passage 27 formed in such head. The passage 27 terminates in the tapering forward surface of the head 4. It is obvious that when the bomb is projected through the water as, for example, by being fired from a gun, water will rush into and through the passage 27 and pressing against 95 the piston 25, will force the plunger rearwardly, thus disengaging the lugs 20 and 21. In order to regulate the rate at which the water enters the cylinder 26, and thus determine the time it will take for the cylin- 100 105 110

der to become full and the piston to act, I provide a slide 28, or the like, having a plurality of holes or openings 29, of varying sizes, any one of which openings may be brought into registry with the mouth of the passage 27. It is obvious that the smaller the opening, the more time will be required to fill the cylinder and operate the piston, and consequently, the greater will be the distance that the bomb will travel under water before the shells are released.

Means are provided for forcibly and automatically separating the two shells immediately upon the release of the lugs 20 and 21. I have shown a spring 30 for this purpose, but obviously other means may be employed. This spring 30 is confined between the plate 7 and the cap 2, a post 31, secured to the cap, serving to limit the compression of the spring. When the lugs 20 and 21 are released by the water pressure acting on the plunger 24, as above described, the spring 30 forcibly ejects the inner shell 3 and its associated parts from the outer shell 1, the separation taking place at the point 6. As the inner shell passes out, the flange 8 will engage one of the lugs 20 and this will pull the plate 7 backward in such manner as to trip the trigger 12 and permit the spring 11 to throw the plunger 10 against the cap 16, thus exploding the charge.

It will be appreciated that the principles above described may be embodied in any desired form of projectile adapted to be fired from the naval guns now in use. When attacking submarines with such a projectile it will not be necessary to accurately estimate the range and set a time fuse, as is the pres-

ent practice, but the timing begins only after the projectile strikes the water. Hence, the charge can be made to explode at any desired depth regardless of the distance the projectile travels before entering the water.

What I claim is:

1. A submarine bomb comprising inner and outer cylindrical shells, co-axially arranged, an explosive charge carried by the inner shell, means for holding said shells together, water-operated means for releasing said holding means, a spring for forcibly separating said shells when the holding means is released, and means operated by the separation of said shells for firing the charge.

2. A submarine bomb comprising inner and outer shells, said shells being normally locked together, an explosive charge carried by the inner shell, a water-pressure operated plunger for disengaging said shells, spring means for separating said shells after said plunger has operated, and means for firing said charge as the shells separate.

3. A submarine bomb comprising inner and outer shells normally locked together, an explosive charge carried by the inner shell, automatic means for separating said shells when unlocked, means for firing the charge by the relative movement of the shells, a cylinder and piston for unlocking said shells, the piston being actuated by water pressure, and the cylinder having a water inlet, and means for varying the size of such inlet.

In testimony whereof I have affixed my signature.

JOHN H. DOWNS.
